UNITED STATES PATENT OFFICE.

ERNST A. HOFFMANN, OF PHILADELPHIA, PENNSYLVANIA, ASSIGNOR TO D. J. NORMOYLE, OF PHILADELPHIA, PENNSYLVANIA.

HAND-TOOL.

1,647,634.

Specification of Letters Patent.

Patented Dec. 17, 1912.

Application filed November 15, 1911. Serial No. 660,454.

To all whom it may concern:

Be it known that I, ERNST A. HOFFMANN, a citizen of the United States, residing in Philadelphia, Pennsylvania, have invented 5 certain Improvements in Hand-Tools, of which the following is a specification.

This invention relates to a novel form of tool such as a screw driver, tap wrench, or the like, and has for its object the provision 10 of a novel combination of parts whereby it shall be possible for an operator to disconnect the handle from the body of the tool in order that one of these parts may be turned in either direction to a greater or less extent relatively to the other.

It is further desired to provide a hand tool having the above noted characteristics in which it shall be possible for the operator 20 to make the necessary connection or disconnection of the handle and body by the use of the palm of that hand which holds or grasps said handle; the arrangement being such as to permit of the adjustment or operation desired with the utmost convenience 25 to the operator.

Another object of my invention is to provide a tool of the above noted class which shall be relatively simple and substantial in construction, convenient to operate, as well 30 as inexpensive to make and not likely to get out of order.

These objects and other advantageous ends I secure as hereinafter set forth, reference being had to the accompanying drawings, in which;—

Figure 1, is an elevation, partly in section, illustrating my invention as applied to a tap wrench; Fig. 2, is a detached perspective of certain parts of the wrench shown in 40 Fig. 1; Fig. 3 is a perspective view showing the sleeve of the handle, and Fig. 4, is a horizontal section on the line *a—a*, Fig. 1.

In the above drawings, 1 represents the 45 chuck of a tap wrench which is provided with an upwardly extending centrally disposed spindle or shank 2, although it is to be understood that any other desired form of tool may be substituted for that shown such, for example, as a screw driver, a drill, 50 etc. In any case, the part 2 and therefore the main portion of the tool, is designed to be turned by means of a handle in this case consisting of a sleeve 3 having cross bars 4, the sleeve being constructed to receive the 55 upper end of said spindle. This latter is

provided at some point, preferably distant from its upper or outer end, with a series of teeth 5 which are designed to removably engage certain other teeth 6 formed on the inside of the sleeve 3; it being possible for the 60 teeth 5 to be disengaged from the teeth 6 when the sleeve is moved longitudinally relatively to the spindle 2. Beyond the teeth 5, the spindle 2 is in the present instance of reduced diameter and the sleeve 3 65 is so formed as to provide a bearing for this part of said spindle as well as for that part thereof on the opposite side of the teeth; its upper end being countersunk for the reception of a head 7 rigidly fixed to said reduced portion 8 of the spindle, in the present instance, by being screwed thereon. Confined between this head and the shoulder 9 formed by the bottom of the countersunk recess in the upper end of the sleeve 75 is a spring 10 designed to normally maintain the teeth 6 of the sleeve 3 in engagement with the teeth 5 of the spindle 2. With this arrangement of parts the said sleeve 3 and therefore the handle as a whole is normally 80 coupled or operatively connected to the sleeve 2 and may be utilized to turn the latter and therefore the chuck or other tool element attached to or forming part thereof.

It is obvious that in using the tool the 85 operator grasps the arm 4 with his fingers so that the head 7 falls within the palm or front portion of his hand, and when, for any reason, it is desirable to turn the handle forward or back relatively to the tool and 90 its sleeve, a tightening of the fingers such as causes a relative movement of the handle 4 and the head 7 toward each other, compresses the spring 10, at the same time freeing the teeth 6 from the teeth 5. The handle 95 4 with the sleeve 3 may then be turned as long as sufficient pressure is exerted on the head 7 to prevent the reengagement of said teeth, although as soon as this pressure is released, the two elements of the tool are 100 again automatically coupled by reason of the expanding action of the spring 10 forcing the teeth 6 of the sleeve 3 toward and into engagement with the teeth 5 of the spindle 2.

From the above it will be seen that the wrench may be used with the utmost convenience and in the quickest manner possible, especially as the two sets of teeth are 105 so designed as to transmit power from the 110

handle to the spindle regardless of which way the former is turned.

I claim;—

The combination in a tool of a shank having an extension of less diameter than its body forming a spindle, and provided with a series of radial teeth on the shoulder between said spindle and its body; a head fixed on the spindle; a sleeve slideable on the spindle; and having portions inclosing a part of the head and the teeth of the shank body respectively; said sleeve having a series of inclosed radial teeth formed to engage the teeth of the shank to cause movement of the latter in either direction; a

spring inclosed by the sleeve and acting on the head of the spindle to force the two sets of teeth together; and a cross bar fixed to the sleeve and projecting at right angles thereto, adjacent the head of the spindle in position to be grasped by the fingers of an operator at the same time that the palm of the hand engages the spindle head.

In testimony whereof, I have signed my name to this specification, in the presence of 25 two subscribing witnesses.

ERNST A. HOFFMANN.
